UNITED STATES PATENT OFFICE.

DAVID MANLY BREDIN, OF PICTON, CANADA.

SELF-CLOSING FAUCET.

SPECIFICATION forming part of Letters Patent No. 673,897, dated May 14, 1901.

Application filed July 10, 1900. Serial No. 23,161. (No model.)

To all whom it may concern:

Be it known that I, DAVID MANLY BREDIN, a subject of Her Majesty the Queen of Great Britain, residing at Picton, in the county of 5 Prince Edward, Province of Ontario, Canada, have invented certain new and useful Improvements in Self-Closing Faucets; and I do hereby declare that the following is a full, clear, and exact description of the invention, 10 such as will enable others skilled in the art to which it appertains to make and use the same.

My invention relates to improvements in self-closing faucets especially designed for use on vessels or casks which contain slow-running 15 fluids, such as molasses and syrups.

One object of the invention is to provide means for automatically closing the faucet or tap when a predetermined quantity of the liquid shall have been drawn from the cask or 20 vessel and, furthermore, to construct the device in a way which permits it to be adjusted so as to vary the period of the closure according to the quantity of liquid which it may be desired to draw from a cask.

25 A further object is to simplify the construction, promote the efficiency and accuracy of the device, and cheapen the cost of manufacture.

Further objects and advantages of the invention will appear in the course of the subjoined description, and the novelty in the combination of devices and in the construction and arrangement of parts will be defined by the claim.

35 To enable others to understand the invention, I have illustrated a preferred embodiment thereof in the accompanying drawings, forming a part of this specification, and in which—

40 Figure 1 is a perspective view of a self-closing faucet embodying my invention. Fig. 2 is a plan view thereof. Fig. 3 is a vertical cross-section taken in the plane of the dotted line 3 3 on Fig. 2. Fig. 4 is a longitudinal 45 sectional view in the plane of the dotted line 4 4 on Fig. 3. .

The same numerals have reference to corresponding parts in each of the several figures of the drawings.

50 10 designates the stem or body of a faucet or tap which may have a male-threaded inner end to adapt it to be secured in a cask, bar-

rel, or other vessel which contains a slow-running liquid, or said stem or body may be attached to the cask by any other preferred 55 means. This stem has a longitudinal liquid-way 11, through which the liquid from the cask is adapted to flow, and at or near its outer end said stem is furthermore provided with a vertical opening 12, the latter intercepting 60 the liquid-way 11. Said vertical opening extends through the stem or body, so as to have its ends exposed on the top and bottom side of the body, the lower part of said opening forming the exit for the liquid which flows 65 through the liquid-way 11.

13 designates the plug, which is fitted snugly in the vertical opening of the body for the purpose of normally closing the liquid-way 11, so as to cut off the flow of the liquid; but this 70 plug is capable of vertical movement in the body or stem of the faucet by the automatic devices of my invention, whereby a plug may be raised on adjustment of the faucet to open the lower part of the vertical opening 12, and 75 thereby establish an outlet for the liquid from the liquid-way 11.

The stem or body is provided at a point near the plug with an upstanding short post 14, across which extends the scale-beam 15. 80 This scale-beam is fulcrumed at a point intermediate of its length to this short post by the bolt or pin 18, so as to form the long and short arms in said scale-beam. The long arm of the scale-beam has a series of gradations 85 16, and on said arm is slidably fitted the counterpoise 17, the latter adapted to traverse the gradations of the beam. The short arm of this beam is provided in its upper edge with a notch 19, adapted to receive a bail, 90 which suspends the vessel-holding platform presently described. Said short arm of the scale-beam is connected operatively with the vertically-movable plug 13, and this connection is effected by the provision of a slot 20 95 in the short arm of the lever, through which slot passes the pivotal pin 21, the latter being fastened to the upper extremity of said plug. It will be noted that the scale-beam and the plug are loosely connected together by a joint, 100 which permits the scale-beam to turn freely on its fulcrum and also enables the plug to have the desired vertical play in the opening of the stem or body, whereby each element

may have the proper movement without the lever binding on the plug, or vice versa.

For the purpose of holding the scale-beam and the plug in positions to close the liquid-outlet through the tap or faucet I employ an automatic latch, which is shown in the form of a spring 22, the same being fastened or attached to the stem in any suitable way. This latch lies close to the vertically-movable plug, and at its upper end said latch is provided with the shoulder 23, the latter adapted to engage with a stud 24. This stud is carried by the vertically-movable plug and at a point which permits it to engage with the shoulder of the latch when the plug is in its lowered position to close the liquid-outlet through the faucet, whereby the plug is locked for the purpose of preventing the escape and waste of the liquid.

20 The vessel into which the liquid is drawn is designed to be placed on a platform 25, to which is fastened the suspending-bail 26. This bail is made from wire, and in the embodiment shown by the drawings the bail is constructed to provide the diverging legs 27. These legs are arranged in pairs at the ends of the bail, and said legs are fastened in any approved way to the edges of the platform. The platform is suspended removably from 30 the scale-beam by fitting the upper portion of the bail over the edge of the short arm of said bail, the bail being received in the notch 19 thereof, thus retaining the bail in place against displacement on the scale-beam.

35 The operation may be described as follows: With the plug in its lowered position to close the liquid-outlet through the faucet the stud 24 engages with the shouldered latch 22, and said plug is thus locked in place to prevent 40 the accidental flow and escape of the liquid. In using the faucet the bail is fitted on the notched edge of the scale-beam to suspend the platform below the liquid-outlet, and this platform supports a vessel in a position to receive the liquid. The operator adjusts the counterpoise on the scale-beam at a point determined by the weight of the liquid which is to be drawn from the cask, and the vessel having been placed on the platform the spring-latch 22 is retracted from engagement with the stud, thus releasing the plug and permitting it to be opened by the weight of the scale-beam and the counterpoise thereon. The liquid now flows through the faucet and 55 into the vessel on the platform until the desired quantity of liquid shall have accumulated in said vessel, at which time the weight of the load in the vessel overcomes the gravity of the counterpoise and pulls downwardly on 60 the short arm of the scale-beam, whereby the stud 24 is automatically engaged with the shouldered latch for the purpose of locking the vertically-movable plug in its lowered position. The plug is thus automatically locked 65 and positively restrained from movement in a manner to cut off the escape of the liquid, and the vessel containing the liquid may now

be removed from the platform without in any wise opening the faucet.

The device is simple in construction, efficient in operation, easily manipulated or controlled, can be attached to any cask or vessel, and can be manufactured at a low cost.

By reference to Figs. 2 and 4 of the drawings it will be noted that the post 14 is arranged on one side of the beam-lever 15, whereas the shouldered latch 22 is fastened to the faucet on the opposite side of said beam-lever. The beam-lever is fulcrumed to this fixed post, and adjacent to the fulcrum-pin a short longitudinal slot is provided in said beam-lever, which slot is adapted to receive a pivotal stud or pin 21, that is fastened to the upper end of an extension on the plug-gate 4, whereby the beam-lever and the plug-gate are loosely connected together by a stud or pin that is adapted to have a limited play in the slot of the beam-lever. This loose connection enables the beam-lever to turn on its fulcrum and the gate-plug to slide in the 90 opening of the faucet-body without disturbing the operative relation of the beam-lever and the plug-gate. It is to be understood that the short arm of the beam-lever travels in an arc of a circle, while the plug-gate is 95 limited to move in a vertical path. This movement of the respective parts cannot be obtained unless a loose connection is employed between them, and this connection is attained in my invention by the provision of the slot 100 in one part and the pin on the other part.

It will be recalled that the lever is locked when it is raised to the operative position shown by Figs. 1 and 3 of the drawings by the engagement of the shouldered latch 22 with the pin 24 on the extension of the plug-gate. When setting the device in use, the shouldered latch is withdrawn from engagement with the pin and the scale-poise is adjusted on the beam-lever, thus freeing the pin 22 from the latch and permitting the plug to ascend under the weight of the scale-poise on the beam-lever. To positively arrest the upward movement of this plug when the liquid-passage in the faucet has been opened 115 to its full extent and to prevent the plug from being wholly withdrawn from the faucet by the action of the scale-poise and the lever, I have provided means for arresting the upward movement of the plug-gate. This means 120 is clearly shown by Fig. 4 of the drawings as consisting of a stop-pin 30, which is attached to the plug in a position to extend into a groove or recess 31, the latter being formed in the faucet-body at one side of the plug, 125 opening therein. This groove or recess 31 terminates near the upper side of the faucet, so as to form a shoulder 32, the latter lying in the path of the stud or pin 30 and adapted to limit the upward movement of the plug-gate. This stop-pin is adapted to travel in the groove or recess to prevent the plug-gate 130 from having any possible tendency to turn in the opening of the faucet-body, and thus any

twisting of the pins 21 24 out of position is prevented.

Having thus described the invention, what I claim as new, and desire to secure by Letters 5 Patent, is—

If a self-closing faucet, the combination of a body provided with a plug-opening and with a vertical groove which terminates in a stop-shoulder, a plug in said plug-opening and 10 having a stop-pin arranged to travel in said groove, a connecting-stud 21 on the upper extremity of the plug, a post fixed to the faucet-body, a scale-beam fulcrumed on the post

and having a longitudinal slot which loosely receives the connecting-stud of the plug, a pin 15 projecting from the opposite side of the plug, a shouldered latch disposed in the path of said pin, and a shiftable poise on the scale-beam, substantially as described.

In witness whereof I have hereunto set my 20 hand in the presence of two witnesses.

DAVID MANLY BREDIN.
